UNITED STATES PATENT OFFICE.

GEORGE HENRY HAWORTH, OF BURNLEY, ENGLAND, ASSIGNOR TO THE BURNLEY AUTOMATIC LOOM, LIMITED, OF MANCHESTER, ENGLAND, AN INCORPORATED COMPANY.

AUTOMATIC FILLING-REPLENISHING LOOM.

SPECIFICATION forming part of Letters Patent No. 790,430, dated May 23, 1905.

Application filed March 25, 1904. Serial No. 200,022.

To all whom it may concern:

Be it known that I, GEORGE HENRY HAWORTH, a subject of the King of Great Britain, and a resident of Burnley, in the county of 5 Lancaster, England, have invented certain new and useful Improvements in Automatic Filling-Replenishing Looms, of which the following is a specification.

This invention relates to self-acting filling-replenishing looms; and it consists in improved arrangements of mechanism suitable for underpick-looms and adapted to insure the certain action of the change motion at high speeds of the loom.

15 On the drawings appended hereunto the improved apparatus or motion is represented, only such parts of the loom being shown as relate to this motion.

Figure 1 shows a vertical cross-section of 20 the shuttle-box and the magazine through the center and looking toward the outer end of the slay with the movable parts in the positions they normally occupy while the weaving proceeds, the slay and magazine being 25 shown in the positions they occupy relatively to one another when the slay is approaching the end of its forward movement; Fig. 2, a similar section of the magazine with the parts in the positions they occupy when the change 30 of the filling-shell is to be effected. Fig. 3 is a section of the magazine through the center looking toward the inner end; Fig. 4, a front view of the magazine and parts of a loom actuating the same; Fig. 5, a side view of the filling-fork lever, and Fig. 6 a plan of the shuttle-box and magazine.

The filling-cops are inclosed in cylindrical cases or shells 1, and the shuttle 2, Fig. 1, has a through-slot from the top to the bottom 40 and is arranged as described in the specification for Patent No. 738,897. The slay-bottom 5 and shuttle-box bottom 4 have a vertical slot 3 cut through them. To the shuttle-box back 18 a casting 6 is fixed, inclosing with 45 the shuttle-box front 15 a curved channel 7, adapted to hold a definite number—say three—cop-shells. The lowest shell 1^c rests upon supports adapted to be pressed back by it

when it is pushed from above, for instance, on sliding carriers 12, pushed inward by 50 springs, Figs. 1 and 5. In front of the slot 7 two carriers 9 are formed on a bar 8, extending in front of the shuttle-box front 15 and having backward extensions 10, which can turn on studs 11, fixed in the ends of the 55 casting 6. A spring 13 is placed round a bolt 14, which is suspended by its head on a lug 15^a, formed on the shuttle-box front 15, and passes freely through the bar 8. A nut 16 serves to tighten the spring and hold up the 60 bar 8 with the carriers 9. These are formed with inclines at the front and concave recesses in their upper sides to retain a cop-shell 1^b in the cavities and press it against two horns 17, cast with the top of the channel 7. 65

Opposite to the channel 7 a hopper or magazine 21 is fixed, which is adapted to contain a number of cop-shells and is fixed to a bracket 19, bolted to the loom side 20. The hopper is open at the top and bottom and has also narrow opening 22 at the outer end for the ends of the filling-yarn, which is threaded through one end of each cop-shells 1, to pass through. The reserve shells contained in the hopper are supported on two concave carriers 23, 70 which are cast on a cross-bar 24. This bar is fixed at each end to a vertical bar 25, adapted to slide up and down in guides 26. The cross-bar 24 is supported by a rod 27, which on the breakage of the weft is actuated in 75 such a manner as to lower the cross-bar 24 and the shell 1^b, resting on the carriers, from the position shown on Fig. 1 into that shown on Fig. 2, when it is at a slightly lower level than the shell 1^b, held on the carriers 9. The 80 shells resting on the bottom shell 1^a are prevented from following it by two fingers 28, which pass under the second shell when the carriers 23 are lowered. This may be effected in the manner shown on the drawings. The 85 fingers 28 form the prongs of a fork, the stem 29 of which slides in guides 30, fixed to the foot 31 of the hopper, and is pulled toward the shells by a spring 32. Between the fingers 28 an inclined finger 33 is fixed to the 90 fork, against which an incline on the cross- 95

bar 24 presses when this bar is in its top position, as shown on Fig. 1, and thereby holds the fingers 28 back. When the cross-bar 24 is lowered, the spring 32 pulls the fingers 28 forward under the second shell in the hopper and holds it up, the fingers being pushed back again when the bar is raised again.

The down-and-up movement of the bar 24 may be effected in any suitable way—for instance, by the mechanism shown on the drawings. The vertical rod 27 is connected at its lower end to a lever 36, which is fulcrumed on a bracket 37, fixed to the loom side 20. On the opposite side of the fulcrum the lever is connected to a vertical rod 39 by a universal joint 40. The upper end of this rod 39 is attached to a lever 41, fixed upon the shaft 42, which carries the lever 43, to which the weft-fork holder 44 is attached at the opposite side of the loom. When the filling breaks or gives out, this lever is turned toward the front by the filling-fork 45 in the well-known manner, the rod 39 is moved upward, and the rod 27, with cross-bar 24 and shell-carriers 23, downward into the position shown on Fig. 2. When the slay now beats up, the inclines on the carriers 9 first lift the shell 1^a against the horns 17 and are then depressed by it, the spring 13 yielding. The shell 1^a presses the shell 1^b back till it takes its place, whereby the shell 1^c in the curved channel 7 is forced down into the shuttle 2, the supports 11 giving way. The spent shell is thereby ejected from the shuttle and falls through the slot 3 upon an inclined chute 46, fixed to the slay-bottom 5, which guides it to the outside of the loom. The supports 12 move forward again as soon as the center of the shell 1^c has passed them and support the other shells in the channel 7. 40 When the change of shells has been effected in this way and the filling-fork is released, a weight 38 on the lever 36 returns the several parts to their position of rest.

I claim as my invention—

45 1. In a loom, a slay having a shuttle-box formed with a curved slot extending upward and forward from the top, of a slotted shuttle in said box adapted to contain several cylindrical filling-shells, carriers pivoted in front 50 of the shuttle-box and adapted to support another filling-shell in front of said slot, springs adapted to secure said shells in their positions and means whereby the shell carried by the carriers will pass into said curved slot.

55 2. In a loom, a slay having fixed thereto castings inclosing a curved slot, extending upward and forward from the shuttle-box toward the front of the slay and adapted to contain several cylindrical filling-shells, carriers pivoted in front of the shuttle-box and adapted to support another filling-shell in front of the others, springs adapted to secure said shells in their positions and means whereby the shell carried by the carriers will pass into said 5 curved slot.

3. In a loom, a slay having a shuttle-box formed with a curved slot extending upward and forward from the top of a slotted shuttle in said shuttle-box toward the front of the slay and adapted to contain several cylindrical filling-shells, carriers pivoted in front of the shuttle-box and adapted to support a front filling-shell before those in the slot, springs adapted to secure said shells in their positions, and means operative on the failure of the filling in the shed and adapted to place another shell into the path of the said front shell and hold it in this position while the slay beats up, and to push said front shell into said slot and the bottom shell contained therein into said slotted shuttle from above.

4. In a loom, a slay, a shuttle-box thereon formed with a curved slot extending upward and forward from the top of a slotted shuttle in said box toward the front of the slay and adapted to contain three cylindrical filling-shells, supports for the said shells adapted to yield against spring-pressure when pressed from above, carriers movable on pivots and adapted to support a fourth shell in front of said slot, a spring pressing said carriers upward and horns projecting from the top of the slot above the carriers, means operative on the failure of the filling in the shed and adapted to place a fifth shell into the path of said fourth shell and hold it in this position while the slay beats up and pushes this shell onto the carriers and the bottom shell in the slot into the loom-shuttle from above, and a slot in the slay-bottom adapted to allow the used filling-shell forced out of the shuttle to drop upon an ejecting-chute.

5. In a loom, the combination of a slay having a shuttle-box and a straight through-slot in the bottom of said shuttle-box and slay, another curved slot the sides of which are attached to said shuttle-box above the loom's shuttle when in the box, said slot being adapted to contain filling-shells and opposite an opening in the shuttle whereby shells may be successively pushed into said shuttle from said slot, carriers projecting at the outer side of said slot and adapted to resiliently support a filling-shell, said carriers being slightly concave, horns extending above said carriers and a spring adapted to coöperate with said horns to hold a filling-shell in the cavities of the carriers.

6. In a loom, a magazine adapted to contain a number of reserve filling-shells, said magazine being fixed onto the loom-frame in front of one of the shuttle-boxes and open at the top and bottom, carriers adapted to support the shells in the magazine and to slide up and down, means operative on the failure of the filling adapted to lower said carriers, sliding fingers and a spring adapted to slide said fingers between the first and second shell resting upon the carriers and means adapted to liberate said fingers and spring when said carriers

are lowered, and to push them back when the carriers are raised again.

7. In a loom, a magazine adapted to contain a number of reserve filling-shells, said magazine being fixed onto the loom-frame in front of one of the shuttle-boxes, and open at the top and bottom; carriers adapted to support the shells in the magazine, sliding fingers adapted to slide between the lowest and second shell supported on said carriers, a rock-shaft, a lever mounted on said rock-shaft, a filling-fork carried on said lever, a second lever fixed on said rock-shaft, a third lever fulcrumed on a pivot below said rock-shaft, a rod connecting said second lever to one limb of the third lever, a rod connected to the opposite limb of said third lever and supporting said carriers, said levers and connections being so arranged that the carriers are lowered when the filling-fork is moved toward the front on the failure of the filling in the shed, a balance-weight on said third lever adapted to raise the carriers when the filling-fork is liberated, and means operated by said carriers and adapted to push back said fingers when the carriers are raised.

8. In a loom, a slay having a shuttle-box formed with a curved slot extending upward and forward from the top of a shuttle in the box and adapted to contain several filling-shells, carriers adapted to support another filling-shell in front of those in the slot, springs adapted to secure said shells in their positions, a magazine adapted to contain a number of reserve filling-shells, said magazine being fixed to the loom-frame in front of said shuttle-box and open at the top and bottom, carriers adapted to support the shells in the magazine, means operative on the failure of the weft to lower said carriers till the shell resting thereon is in the path of the shell supported in front of the curved slot, sliding fingers and a spring adapted to slide said fingers between the first and second shell resting upon said carriers, and means adapted to liberate said fingers and spring when said carriers are lowered and to push them back when the carriers are raised again.

9. In a loom the combination of a slay having a shuttle-box and a straight through-slot in the bottom of said shuttle-box and slay, a curved slot the sides of which are attached to said shuttle-box above the loom-shuttle when in the box, said slot extending upward and forward and being adapted to contain filling-shells and opposite an opening in the shuttle whereby shells may be successively pushed into said shuttle from said slot, carriers projecting at the outside of said slot and adapted to resiliently support a filling-shell at the opening of said slot, said carriers being slightly concave, horns projecting above said carriers,

a spring adapted to coöperate with said horns to hold a filling-shell in the cavities of the carriers, a magazine fixed to the loom-frame in front of said curved slot and adapted to contain a number of reserve filling-shells, said magazine being open at the bottom, carriers adapted to support said reserve filling-shells, means operative on the failure of the filling adapted to lower said carriers till the shell resting thereon is in the path of the shell supported in front of said curved slot, sliding fingers and a spring adapted to slide said fingers between the first and second shell resting upon said carriers, and means adapted to liberate said fingers and spring when the carriers are lowered and to push them back when the carriers are raised again.

10. In a loom the combination of a slay, a shuttle-box thereon formed with a curved slot extending upward and forward from the top of a slotted shuttle in said box toward the front of the slay and adapted to contain several cylindrical filling-shells, supports for the said shells adapted to yield against spring-pressure when pressed from above, carriers movable on pivots and adapted to support another shell in front of said slot, horns projecting from the upper side of the slot above the carriers, a spring adapted to coöperate with said horns to hold said shell on the carriers, a magazine adapted to contain a number of reserve filling-shells, said magazine being open at the bottom, carriers adapted to support the shells in the magazine and to slide up and down, fingers and a spring adapted to slide said fingers between the first and second reserve shell on said carriers, an incline connected to said carriers adapted to push said fingers back when the carriers are raised and to liberate them when the carriers are lowered, a rock-shaft, a lever mounted on said rock-shaft, a filling-fork carried on said lever, a second lever fixed on said rock-shaft, a third lever fulcrumed on a pivot below said rock-shaft, a rod connecting said second lever to one limb of the third lever, a rod connected to the opposite limb of said third lever and supporting said reserve shell-carriers, said levers and connections being so arranged that the carriers are lowered when the filling-fork is moved toward the front on the failure of the filling in the shed, and a balance-weight on said third lever adapted to raise the carriers when the filling-fork is liberated.

In testimony whereof I have hereunto set my hand in the presence of two witnesses.

GEORGE HENRY HAWORTH.
